COMBINED CIGARETTE HOLDER AND ASHTRAY

Mary B. Johns, 413 S. 11th St., Cambridge, Ohio

Filed Nov. 21, 1963, Ser. No. 77,517

Term of patent 14 years

(Cl. D85—2)

FIG. 5

FIG. 1 is a front elevational view of a combined cigarette holder and ashtray showing my new design;

FIG. 2 is a side elevational view;

FIG. 3 is a top plan view;

FIG. 4 is an exploded pictorial view showing the cigarette containing base and upper ashtray in vertical separation, the cigarette shown in broken lines being for illustrative purposes only; and

FIG. 5 is a rear elevational view.

I claim:

The ornamental design for a combined cigarette holder and ashtray, as shown and described.
